STOKER

William L. Lentz, Tuckahoe, N. Y., assignor to The Standard Stoker Company, Incorporated, a corporation of Delaware

Application May 4, 1939, Serial No. 271,695

8 Claims. (Cl. 110—105.5)

This invention relates to stokers of the type delivering fuel to the firing opening in an upright wall of a furnace and employing an upper fuel distributing member against the underside of which, fuel is propelled in a forward and upward direction by means of a blast of fluid issuing from a distributor jet head for scattering it over all parts of the furnace firebed.

The fuel distributing elements of a stoker of this type are in the proximity of the firing opening and one object of the invention is to provide a construction thereof that will minimize the dust in the firing opening resulting among other things from the fuel striking the under side of the upper fuel distributing member.

The upper fuel distributing member or top deflector because of its proximity to the fire in the furnace will gradually burn away and deteriorate to an extent requiring replacement thereof, and it is therefore another object of the invention to provide a construction and combination of elements that will prolong the life of the top deflector.

In firing a furnace it is important to maintain an even distribution of fuel over the entire firebed if it is desired to obtain maximum efficiency and economy, it is therefore another object of the invention to provide a construction and arrangement of the distributing elements permitting convenient control of distribution of fuel over the firebed.

Other objects and advantages of the invention residing in the construction, relation and arrangement of elements will become apparent from the following description and claims when considered in connection with the accompanying drawings, in which

Fig. 1 is a vertical, longitudinal sectional view through the rearward portion of a locomotive and the novel stoker, taken on the line 1—1 of Fig. 2, parts being shown in elevation;

Fig. 2 is a sectional view taken on the irregular line 2—2 of Fig. 1;

Figure 3 is a sectional view taken on the lines 3—3 of Figs. 1 and 2, parts being broken away; and

Figure 4 is a sectional view taken on the line 4—4 of Fig. 1.

In the drawings, the letter L refers generally to the locomotive which comprises a firebox 10 provided with a grate 11, and an upstanding rear wall 12 having a firing opening 13 therein. The locomotive cab deck 14 extends rearwardly from the firebox rear wall 12 below the level of the firing opening 13.

Fuel is conveyed from a tender (not shown) to the locomotive firebox 10 by a stoker indicated generally by the letter S. The stoker S includes a conduit 15 leading forwardly from the tender, universally connected at its forward end, by a ball and socket connection 16, to the lower end of an elevating conduit 17. The elevating conduit 17 extends upwardly and forwardly through the cab deck 14 and is surmounted by a casing 18 communicating with and embracing the firing opening 13. The casing 18 is provided with an aperture 19 opposite and in approximate register with the firing opening 13, and a door 20 supported by the casing 18 forms a movable closure therefor.

Fuel is conveyed forwardly and upwardly toward the firing opening 13 by a conveyor screw 21 disposed within the conduit 17. At its lower end the conveyor screw is flexibly connected within the ball and socket connection 16 to a conveyor screw 22 disposed within the conduit 15. Fuel is conveyed by the conveyor screw 21 into the zone of action of a pressure fluid distributor head 23 located at the lower portion of the firing opening, which is arranged to emit fluid, preferably steam, under pressure for projecting fuel into the firebox.

The lower portion of the casing 18 is recessed in its bottom, as indicated at 24, the recess extending between the side walls 25 and 26 of the casing 18. Within the recess 24 is fitted the pressure fluid head 23, forming the bottom wall of the lower tubular portion 27 of the casing 18. For the purpose of securing the pressure fluid head 23 upon the seats 28 and 29, formed in the respective sidewalls 25 and 26, a set screw 30 is threaded into each side wall for engaging lugs 31 formed on the rearward portion of the pressure fluid head 23.

The pressure fluid head 23 is divided longitudinally into a plurality of chambers 32, for purpose of illustration four such chambers are shown in the present embodiment, though it is apparent that any number may be provided. Supply lines 33 supply fluid under pressure to the chambers 32. At its upper forward end, within the firing opening 13, the pressure fluid head 23 is provided with a transversely extending sloping wall 34 provided with a double row of laterally spaced jet openings 35 communicating with the chambers 32. The jet openings 35 are directed forwardly and upwardly, the pressure fluid blasts emitted therefrom being directed against the underside of a deflector plate 36 disposed in the upper portion of the firing opening 13. Any num- 55

ber of rows of jet openings 35 may be provided and they are preferably arranged with the jet openings in staggered relation. The pressure fluid head 23 is provided with a lip 37 extending 5 upwardly and forward from the side edges and the forward edge of the perforated wall 34. The lip 37 functions to retain the fuel momentarily as it rolls or drops over the upper edge of the perforated wall 34 so that all the fuel is acted 10 upon by the blast issuing from the jet openings 35 and preventing fuel from rolling or dropping over the forward and side edges of the wall 34 and accumulating on the wall 38 defining the bottom of the firing opening.

15 The top deflector 36 is preferably divided longitudinally into two substantially symmetrical halves 39 and 40 so that they may be individually adjusted about their respective rearward ends to any one of a number of relative positions about 20 a horizontal transverse axis. The deflector members 39 and 40 are provided with the hollow hubs 41 and 42, respectively, interfitting at their adjacent ends by means of a projection 43, circular in cross section and formed with the hub 41 and 25 arranged to be received in the recess 44 formed in the hub 42. The hollow hubs 41 and 42 are provided with the chambers 8 and 9, respectively, opening through the opposite ends of the hubs 41 and 42. Fluid under pressure is supplied to the 30 chambers 8 and 9, as for example steam, by means of supply pipes 6 and 7. The opposite ends of the hubs 41 and 42 of the deflector members are rotatably mounted in the bearing members 45 and 46, respectively. Recesses 47 and 48 35 are provided in the upper rearward edges of the casing sidewalls 25 and 26, respectively, in which are received the bearing members 45 and 46, respectively. The bearing members 45 and 46 are provided with flanges 49 and 50, respectively, 40 overlapping the casing sidewalls 25 and 26, respectively, the bearing members being secured to the casing sidewalls in any suitable manner as by means of bolts passing through the flanges into the casing sidewalls. Thus, by opening the 45 firedoor 20 and removing the bearings 45 and 46, the deflector 36 can be removed or placed in position through the opening 19 at the rear of the casing 18. A tongue 51 extending downwardly and rearwardly from the top wall of the casing 50 18 provides an additional bearing surface for the interfitting ends of the hubs 41 and 42.

The deflector member 40 will now be described in detail, it being understood that the deflector member 39 is similarly constructed. An arm 52 55 having a chamber 53 formed therein extends downwardly and forwardly from the hub 42 to the firing opening 13, and a plate-like member 54 extends forwardly from the arm 52 through the upper portion of the firing opening at a lesser angle to the horizontal than the arm 52. The chamber 53 in the arm 52 communicates at one end with the chamber 9 in the hub 42, and a plurality of jet openings 55 in the front wall of the arm 52 communicate with the chamber 53. 60 The jet openings 55 are disposed subjacent the rearward end of the plate-like member 54 and directed to emit blasts of fluid under pressure into the firebox and across the under side of the member 54. The blasts of fluid under pressure 65 emitted from the jet openings 55 serve to cool the plate-like member 54, thus prolonging the life thereof; they also function to eliminate dust in the firing opening by blowing the dust, formed when fuel is projected against the underside of 70 the member 54 by the pressure fluid emitted from 75

the jets 34, into the fire-box; and they also cooperate with the blasts issuing from the jets 34 to project fuel into the firebox.

The hub 42 is preferably also provided with a plurality of jet openings 56 directed downwardly 5 against the upper surface of the plate-like member 54 functioning to eliminate dust in the firing opening and effecting a cooling action on the member 54, thereby prolonging its life.

In order to control distribution of fuel over the 10 firebed in the firebox the deflector members 39 and 40 are arranged for adjustment to any one of a number of positions about the axis of their hubs 41 and 42, respectively, by the handles 51 and 58, respectively, which are secured in any 15 suitable manner to that portion of the hubs 41 and 42 projecting beyond the bearing members 45 and 46. The deflector members may be locked in any of their adjusted positions by means of the pins 59 and 60 which are arranged to be 20 inserted through holes 61 and 62 in the handles 57 and 58, respectively, and into any one of a plurality of holes 63 and 64 in the flanges 49 and 50, respectively. The deflector members 39 and 40 are independently adjustable so that distribution 25 may be controlled over either side of the firebed independently of the other side.

Depending from the underside of the deflector members 39 and 40 are the forwardly and outwardly curving ribs 65 and 66 respectively. These 30 ribs intercept a portion of the fuel projected against the deflector members 39 and 40 by the pressure fluid blasts emitted from the jet openings 35, and direct it to the rear corners of the firebox.

35 I claim:

1. A stoker for a firebox having an upstanding wall with a firing opening therein, said stoker comprising a fuel feed conduit communicating with said opening, fuel projecting means at the 40 discharge end of said conduit, means for delivering fuel to said projecting means, a transverse wall disposed in said firing opening above said fuel projecting means, said projecting means being arranged to propel fuel in an upward and 45 forward direction against the underside of said transverse wall, and means subjacent the rearward end of said transverse wall for emitting a blast of fluid under pressure forwardly across the underside of said transverse wall, said last 50 named means being so disposed that the fluid under pressure issuing therefrom strikes the fuel only after projection thereof by said fuel projecting means.

2. A stoker for a firebox having an upstanding 55 wall with a firing opening therein, said stoker comprising a fuel feed conduit communicating with said opening, a pressure fluid head at the discharge end of said conduit, means for delivering fuel to said pressure fluid head, a transverse wall disposed in said firing opening above said head, said head having a plurality of jet openings directed upwardly and forwardly toward the underside of said transverse wall, and a pressure fluid head at the rearward end of said 60 transverse wall, said last named head having a plurality of forwardly directed jet openings below the level of the under side of said transverse wall and above the level of said first named jet openings, said last named head being so disposed that the fluid under pressure issuing therefrom strikes the fuel only after projection thereof by the fluid under pressure issuing from said first named head.

3. A stoker for a firebox having an upstanding 75

wall with a firing opening therein, said stoker comprising a fuel feed conduit communicating with said opening, fuel projecting means at the discharge end of said conduit and a fuel deflecting member disposed in said firing opening above said fuel projecting means, means for delivering fuel to said projecting means, said projecting means being arranged to propel fuel in an upward and forward direction against the under side of the forward portion of said deflecting member, said deflecting member being provided in its rearward portion with a chamber communicating with a source of fluid under pressure, said chamber having a front wall intermediate the ends of said deflecting member and depending therefrom, said front wall being provided with jet openings communicating with said chamber and directed forwardly across the under side of the forward portion of said deflecting member, said front wall being so disposed that the fluid under pressure issuing from the jet openings therein strikes the fuel only after projection thereof by said fuel projecting means.

4. A stoker for a firebox having an upstanding wall with a firing opening therein, said stoker comprising a fuel feed conduit communicating with said opening, a pressure fluid head at the discharge end of said conduit and a fuel deflecting member disposed in said firing opening above said head, means for delivering fuel to said pressure fluid head, said head having a plurality of jet openings directed upwardly and forwardly toward the under side of the forward portion of said deflecting member, said deflecting member being provided in its rearward portion with a chamber communicating with a source of fluid under pressure, said chamber having a front wall intermediate the ends of said deflecting member and depending therefrom, said front wall being provided with jet openings communicating with said chamber and directed forwardly across the under side of the forward portion of said deflecting member, said front wall being so disposed that the fluid under pressure issuing from the jet openings therein strikes the fuel only after projection thereof by said pressure fluid head.

5. A stoker for a firebox having an upstanding wall with a firing opening therein, said stoker comprising a fuel feed conduit communicating with said opening, fuel projecting means at the discharge end of said conduit, means for delivering fuel to said projecting means, a transverse wall disposed in said firing opening above said fuel projecting means, said projecting means being arranged to propel fuel in an upward and forward direction against the under side of said transverse wall, means subjacent the rearward end of said transverse wall for emitting a blast of fluid under pressure forwardly across the under side of said transverse wall, said last named means being so disposed that the fluid under pressure issuing therefrom strikes the fuel only after projection thereof by said fuel projecting means, and means rearward and above said transverse wall for emitting a blast of fluid under pressure forwardly across the upper surface of said transverse wall.

6. A stoker for a firebox having an upstanding wall with a firing opening therein, said stoker comprising a fuel feed conduit communicating with said opening, fuel projecting means at the discharge end of said conduit and a fuel de-

flecting member disposed in said firing opening above said fuel projecting means, means for delivering fuel to said projecting means, said projecting means being arranged to propel fuel in an upward and forward direction against the under side of said deflecting member, said deflecting member being provided in its rearward portion with a chamber communicating with a source of fluid under pressure, said deflecting member being provided with jet openings communicating with said chamber and directed forwardly across the under side of the forward portion of said deflecting member, said jet openings being so disposed that the fluid under pressure issuing therefrom strikes the fuel only after projection thereof by said fuel projecting means, said deflecting member being also provided with jet openings communicating with said chamber and directed forwardly across the upper surface of the forward portion of said deflecting member.

7. A stoker for a firebox having an upstanding wall with a firing opening therein, said stoker comprising a casing embracing said firing opening, fuel projecting means adjacent the lower forward end of said casing, means for delivering fuel to said projecting means, fuel deflecting means pivotally mounted at its rearward end in said casing for movement about a horizontal transverse axis, said deflecting means extending forwardly through said firing opening above said projecting means, said projecting means being arranged to propel fuel in an upward and forward direction against the under side of said deflecting means, said deflecting means being provided in its rearward portion with a chamber communicating with a source of fluid under pressure, jet openings intermediate the ends of said deflecting member communicating with said chamber and directed forwardly across the under side of the forward portion of said deflecting member, said jet openings being so disposed that the fluid under pressure issuing therefrom strikes the fuel only after projection thereof by said fuel projecting means.

8. A stoker for a firebox having an upstanding wall with a firing opening therein, said stoker comprising a casing embracing said firing opening, fuel projecting means adjacent the lower forward end of said casing, means for delivering fuel to said projecting means, fuel deflecting means including a hollow transverse extending horizontal hub rotatably mounted in said casing, a deflecting plate-like portion disposed in the firing opening above said projecting means and a chambered arm connecting said hub portion with said deflecting plate-like portion, the chamber in said arm portion communicating with the hollow hub, said hollow hub communicating with a source of fluid under pressure, said arm portion being provided with jet openings communicating with the chamber therein, said jet openings being located and directed to emit a blast of fluid under pressure forwardly across the under side of said deflecting plate-like portion, said hub portion being provided with jet openings directed to emit a blast of fluid under pressure forwardly across the upper surface of said deflecting plate-like portion, and said fuel projecting means being arranged to propel fuel in an upward and forward direction against the under side of said deflecting plate-like portion.
